UNITED STATES PATENT OFFICE.

KATHRYN L. VALENTINE AND GEORGE RAMSEY, OF JERSEY CITY, NEW JERSEY.

DESIGN FOR AN OVERSHOE.

Application filed September 16, 1927. Serial No. 23,443. Term of patent 14 years.

To all whom it may concern:

Be it known that we, KATHRYN L. VALENTINE and GEORGE RAMSEY, both citizens of the United States, and residents of Jersey City, county of Hudson, State of New Jersey, have invented a new, original, and ornamental Design for Overshoes, of which the following is a specification, reference being had to the accompanying drawing, forming a part thereof.

In the drawing:

Figure 1 is a front elevation of an overshoe constructed in accordance with our new design.

Figure 2 is a side elevation thereof, and Figure 3 is a rear elevation thereof.

We claim:

The ornamental design for an overshoe substantially as shown.

**KATHRYN L. VALENTINE.
GEORGE RAMSEY.**
